UNITED STATES PATENT OFFICE.

CHARLES S. MOORE, OF GRAND RAPIDS, MICHIGAN.

EXTENSION-DRAWER SUPPORT.

Application filed January 21, 1925. Serial No. 3,855.

This invention relates to an improved extension drawer support and seeks, among other objects, to provide a structure which will sustain the drawer for free sliding movement and will rigidly support the drawer when drawn out its entire length.

The invention seeks, as a further object, to provide a support embodying means for adjustably elevating or lowering the inner 10 end of the drawer as well as means for adjustably elevating or lowering the outer end of the drawer so that the drawer may be readily leveled and maintained in level position.

Another object of the invention is to provide a support wherein the drawer will be locked to the support so that the drawer can not become accidentally displaced when drawn out but wherein the drawer may be 20 readily detached and removed when so desired.

And the invention seeks, as a still further object, to provide a support which will be quiet and smooth in operation and wherein 25 friction will be largely overcome so that the drawer may be shifted with but little effort.

Other and incidental objects will appear hereinafter.

In the accompanying drawings:

Figure 1 is a side elevation showing my improved support in connection with a conventional drawer and cabinet, parts being shown in section.

Figure 2 is a side elevation showing the 35 drawer drawn out.

Figure 3 is a transverse sectional view on the line 3—3 of Figure 2, looking in the direction indicated by the arrows.

Figure 4 is a detail sectional view on the 40 line 4—4 of Figure 2, looking in the direction indicated by the arrows.

Figure 5 is a detail sectional view on the line 5—5 of Figure 2, looking in the direction indicated by the arrows.

Figure 6 is a detail view showing the 45 connection between the extension arm of the support and the adjusting lever at the forward end of the drawer.

Figure 7 is a detail view showing the 50 manner in which the drawer is detached.

Referring now more particularly to the drawings, I have, for convenience, shown my improved support in connection with a conventional cabinet 10 having side rails 11.

55 A drawer is indicated at 12 and since the structure employed at each side of the

drawer is identical, a description of the illustrated structure at the left of the drawer will suffice for both. As will be understood, I have, in showing the support in connection with a cabinet, merely illustrated a typical mounting of the support and, of course, the support may be employed in connection with any other structure which is formed to contain drawers.

Referring now more particularly to Figure 1 of the drawings, I employ a pair of vertical front and rear end bars 13 and 14 which are fixed at their ends to the rails 11 of the cabinet 10, and connecting said end bars is a pair of spaced parallel upper and lower track rails 15 and 16 extending horizontally between said bars. Rigidly fixed to the rear end bar 14 at a point midway between the rails 15 and 16, is, as particularly shown in Figure 5, an inwardly projecting stud 17 and pivotally connected at its inner end to said stud is an extensible arm 18 of the lazy tong type. Preferably, suitable washers, as indicated at 19, are arranged between the cross straps of the arm, upon the pivots thereof, so that the straps may freely swing with respect to each other, and rigidly fixed to the free end of one of the outermost straps of said arm to extend through the free end of the other of the outermost straps of the arm is a stud 20.

As shown in Figure 4, the stud is somewhat longer than the combined thickness of said straps and is provided at its projecting end with a head 21 while, at opposite sides thereof, the stud is formed with parallel flat faces 22.

Lying between the arm 18 and the track rails 15 and 16 is a carrier 23 in the nature of a plate which is provided with a pair of depending legs 24 and secured to said legs is a pair of horizontal carrier track rails 25 disposed in parallel relation. Mounted upon the carrier 23 is a pair of spaced lower rollers 26 journaled upon studs 27 extending through the carrier and journaled upon a like stud 28, in a plane between the rollers 26, is an upper roller 29. These rollers are

preferably of fiber or some other appropriate composition so as to eliminate noise and are grooved to fit the confronting edges of the rails 15 and 16, the upper roller being disposed to coat with the lower edge of the rail 15 and the lower rollers being disposed to coat with the upper edge of the rail 16. Thus, these rollers will support the carrier

for free movement along the track rails. Fixed to the carrier adjacent the forward and rear edges thereof are bumpers 30 and 31 which are preferably of rubber and fixed to the front end bar 13 is a cleat 32 which, when the carrier is shifted forwardly, will be engaged by the bumper 30 for limiting the carrier in its forward movement, the cleat thus forming a stop for the carrier. Furthermore, this cleat will also serve to reinforce the front end bar and, as shown in Figure 5, the rear end bar 14 is also provided with like reinforcing cleats 33. Mounted upon the upper track rail 15 near the rear end thereof, is an angle shaped stop plate 34, one arm of which depends from said rail, and extending through the other arm of said plate is a bolt 35 which is freely accommodated by a slot 36 in said rail. The stop plate is thus mounted so that the depending arm thereof will coact with the bumper 31 for limiting the carrier in its rearward movement and, as will be at once appreciated, provision is made whereby this plate may be readily adjusted longitudinally of the rail 15 for varying the rearward travel of the carrier. Rigidly fixed to the carrier medially thereof is a pivot stud 37 which extends through a pair of the cross straps of the arm 18 at the point of intersection of said straps and serves to connect the carrier with the arm at a point midway between the ends thereof. Thus, as the arm is extended or collapsed, the carrier will be caused to shift along the track rails 15 and 16.

Pivoted medially upon the adjacent side of the drawer 12 near the rear end thereof and close to the bottom of the drawer, is a lever 38. Pivoted medially upon the rear end of said lever is a roller 39 like the rollers 26 and 29. The roller 39 is grooved to fit between the rails 25 of the carrier 23, and formed in the forward end of the lever 38 is a transverse slot 40 accommodating a clamp screw 41 sunk into the adjacent side of the drawer. Pivoted medially upon the adjacent side of the drawer near the forward end thereof, as well as near the upper edge of the drawer, is a second lever 42, the rear end of which is, as particularly shown in Figures 6 and 7 of the drawings, provided with like notches 43 and 44. Formed in the forward end of said lever is a transverse slot 45 accommodating a bolt 46 which extends through the adjacent side of the drawer and carries a clamping nut 47. At its forward terminal the lever is further provided with an out-turned thumb lug 48. In mounting the drawer, the arm 18 is first extended, as shown in Figures 2 and 7, when the roller 39 of the lever 38 is inserted between the rails 25 of the carrier. The lever 42 is then, as shown in Figure 7, swung up, while the forward end of the drawer is slightly elevated until the

mouth of the notch 43 is disposed to accommodate the flat sides 22 of the stud 20 at the outer end of the arm 18. Thus, the lever may then be swung downwardly slightly to engage the lever with said stud, when the lever is secured by the clamping nut 47. Accordingly, when the outer end of the drawer is released, the stud 20 will lie cross-wise of the notch 43 of the lever 42 while the stud will, as shown in Figure 4, be retained against endwise movement through said notch by the head 21 of the stud. Accordingly, the drawer will be locked to the arm 18 and, as will be appreciated, cannot become accidentally released when the drawer is drawn out.

As will now be seen in view of the foregoing, the weight of the drawer will be communicated to the carrier and supported by the carrier rollers in conjunction with the roller 39 of the lever 38, which latter roller will coact with the rails 25 of the carrier to support a portion of the weight of the drawer. The drawer may thus be easily moved inwardly or outwardly and although the carrier moves with the arm 18, still, the rails 25 are of such length that, at no time, will the roller 39 become displaced from between the rails. Furthermore, attention is particularly directed to the fact that by loosening the screw 41, the lever 38 may be rocked for raising or lowering the inner end of the drawer while by loosening the nut 47, the lever 42 may be rocked for raising or lowering the outer end of the drawer. The drawer may thus be readily leveled upon the support and adjustment easily made from time to time to maintain the drawer in level position.

To detach the drawer, the lever 42 is shifted to the position shown in Figure 7 and the forward end of the drawer slightly elevated, when the lever may be swung up to disengage the stud 20. The drawer may then, of course, be pulled forwardly and displaced. The slot 44 in the lever is provided so that the lever may be mounted at the right side of a drawer instead of the left as shown, when said slot would be disposed to engage the stud 20 of the arm 18 at said side of the drawer. Thus, in practice, no attention need be given the question of mounting the lever at a particular side of the drawer.

Having thus described the invention, what I claim is:

1. A device of the class described comprising a fixed track for a horizontally slidable part, a carrier mounted to travel on the track, a supplemental track movable with the carrier, a lazy tongs connected at opposite ends to the fixed track and slidable part, respectively, and intermediate its ends to the carrier, and an auxiliary support on the said slidable part and mounted on said supplemental track.

2. A device of the class described comprising a fixed track for a horizontally slidable part, a carrier mounted to travel on the track, a supplemental track movable with the carrier, a lazy tongs connected at opposite ends to the fixed track and slidable part, respectively, and intermediate its ends to the carrier, a member pivoted intermediate its ends to the said slidable part, a supporting element at one end of the pivoted member mounted on the supplemental track, and means adjustably connecting the opposite end of the pivoted member to the slidable part.
- 15 3. A device of the class described comprising front and rear bars and a track connecting said bars for slidably supporting a movable part, a carrier movable on the track, a lazy tongs connected at one end to the rear bar and intermediate its ends to the carrier, a member pivoted intermediate its ends to the said movable part, means adjustably connecting one end of the pivoted member to the movable part and means detachably connecting the forward end of the lazy tongs to the other end of the pivoted member.
4. A device of the class described comprising front and rear bars and a track connecting said bars for slidably supporting a movable part, a carrier movable on the track, a lazy tongs connected at one end to the rear bar and intermediate its ends to the carrier, a member pivoted intermediate its ends to the said movable part and having a notch at one end, means adjustably connecting the other end of the pivoted member to the said movable part, and a stud at the forward end of the lazy tongs detachably engaging the notched end of the pivoted member.
5. A device of the class described comprising front and rear bars and a track connecting said bars for slidably supporting a movable part, a carrier movable on the track, a lazy tongs connected at one end to the rear bar and intermediate its ends to the carrier, said movable part being supported by the said track and carrier and connected to the forward end of the lazy tongs, a supplemental track connected with the carrier and movable therewith, and a support movable on the supplemental track and adjustably connected with the aforesaid movable part.
- 20 6. A device of the class described comprising front and rear bars and a track connecting said bars for slidably supporting a movable part, of a carrier movable on the track, a lazy tongs connected at one end to the rear bar and intermediate its ends to the carrier, said movable part being supported by the said track and carrier, means adjustably connected to the movable part and detachably connecting the forward end of the lazy tongs with the said movable part, a supplemental track connected with the carrier and movable therewith, and a support movable on the supplemental track and adjustably connected with the before mentioned movable part.
